COMBINATION HOLSTER, HANDCUFF AND CARTRIDGE CARRIER

Joseph E. Adams, 4244 Mount Vernon Drive,
Los Angeles, Calif. 90008

Filed Nov. 19, 1973, Ser. No. 416,728

Term of patent 14 years

Int. Cl. D22—99

U.S. Cl. D22—13

FIG. 1

FIG. 2

FIG. 3

FIG. 4

FIG. 1 is a perspective view of the combination holster, handcuff and cartridge carrier from the front thereof.

FIG. 2 is the same as FIG. 1 except that it is a view from one side thereof.

FIG. 3 is the same as FIG. 1 except that it is a view from the rear thereof.

FIG. 4 is the same as FIG. 2 except that it is a view from the opposite side thereof.

I claim:

The ornamental design for the combination holster, handcuff and cartridge carrier, as shown.
